UNITED STATES PATENT OFFICE.

ANTENOR NYDQVIST, OF TROLLHATTAN, SWEDEN.

HYDRAULIC TRANSFORMER, TURBINE, OR THE LIKE.

Application filed December 5, 1924. Serial No. 754,112.

To all whom it may concern:

Be it known that I, ANTENOR NYDQVIST, a citizen of the Kingdom of Sweden, residing at Trollhattan, Sweden, have invented 6 new and useful Improvements in Hydraulic Transformers, Turbines, or the like, of which the following is a specification.

In my pending patent application Serial No. 743,730 filed October 15, 1924, I have 10 described an improvement in hydraulic transformers, turbines, pumps, compressors or the like the object of which is to permit, without any change in the efficiency, variation 15 of the ratio of gearing of hydraulic transformers, the number of revolutions and the turning moment of turbines, and the pressure and output of compressors and pumps.

According to the said application one 20 of the blade wheels at least is provided with blades composed wholly or partially of movable members which, in order to constitute blade rims, are secured to concentric rings, disks or the like capable of axial 25 displacement.

According to the present invention the same result may be obtained by mounting the disks or rings carrying the movable blade members so that they may rotate independently 30 relatively to each other and to a common shaft or be locked thereto to rotate with said shaft.

In the drawing several arrangements embodying the invention are illustrated.

Fig. 1 is a longitudinal section of one 35 half part of a hydraulic transformer according to the invention.

Fig. 2 is a side-elevation of the locking mechanism of said transformer.

Fig. 3 shows curves representing the moment and output of the transformer shown in Fig. 1.

With reference to Figs. 1 and 2, the numeral 1 indicates the driving or primary 45 shaft and 2 is the driven or secondary shaft. Secured to the shaft 1 which is connected directly or indirectly to a power engine or other power source, is a blade wheel 3 (the primary wheel), and secured to the shaft 50 2 is a blade wheel 4 (the secondary wheel). Surrounding the secondary wheel 4 is one blade ring 5, the hub of which is rotatably mounted on the secondary shaft 2 or, as shown, on the hub of the secondary wheel 4.

The ring 5 is, in turn, surrounded by a ring 6 which may be secured to the sec-

ondary wheel 4 in any suitable manner as by a ring 40 secured to the ring 6 by means of screws or the like and screwed on a threaded portion of the hub of the sec- 60 ondary wheel.

The ring 5 is formed with a toothed rim 7 adapted to be engaged by a pawl 8 pivoted at 9 to the member 6. An arm 10 secured to the pivot pin 9 is connected by a link 11 to one end of a bell crank lever 12 pivoted at 13, the other end of which engages a slot formed in a bushing or sleeve 14 mounted to slide upon the shaft 2 under the control of a centrifugal governor 15 comprising a weight carried by one arm of a bell crank lever 16 the other arm of which 70 engages a slot formed in the bushing or sleeve 14. The deflection of the centrifugal governor under the control of the cen- 75 trifugal force is counteracted by a spring 17.

In operation, when the secondary shaft is at rest or rotates at low speed, the centrifugal governor maintains the pawl 8 into engagement with the toothed rim 7 so that the 80 ring 5 is caused to rotate together with the secondary wheel and will, consequently, positively operate the secondary shaft. At higher speed of the secondary shaft the centrifugal governor deflects thereby causing 85 the pawl to release the toothed rim 7 so as to allow the blade ring 5 to rotate freely at the speed determined by the blade position, without yielding any work.

The secondary wheel will thus together 90 with its blade ring 5 form a slowly running turbine disk of large turning moment, while with the blade ring 5 released the secondary wheel will represent a more efficient turbine wheel as far as the maximum speed is concerned, with a turning moment correspond- 95 ing to said speed.

In Fig. 3 of the drawing the line *a* represents the turning moment of the transformer in Fig. 1 as obtained when the ring 5 is 100 coupled to the wheel 4. The line *b* represents the turning moment as obtained when the ring 5 is released from the wheel 4.

The curve *c* represents the output correspond- 105 ing to the moment represented by the line *a*, and the curve *d* represents the output corresponding to the moment represented by the line *b*.

The resulting output curve (indicated by heavy lines) will thus maintain itself sub- 110 stantially constant over a broader speed range.

While, in hitherto known designs, as, for instance, Föttinger transformers, a braking of the driven shaft so as to prevent said shaft from rotation will result in a turning moment amounting at most to 1.6—1.8 times the moment acting at the most favorable speed, and the efficiency at the most favorable or normal number of revolutions will reach its maximum and at both sides thereof will very rapidly decrease towards zero parabolically, a braking of the driven shaft of the above described apparatus so as to prevent said shaft from rotation will result in a considerable and automatic increase of the turning moment up to a magnitude several times as large as the normal moment, while maintaining the efficiency substantially constant within a broader speed range. This means that an apparatus constructed on the principles above set forth is especially adapted for the propelling of vehicles, requiring high starting moments. In a power driven vehicle, as an automobile, the change speed gear may, thus, be substituted with advantage by the above described type of mechanism. The operation is in such case somewhat as follows:

When an automobile running on a horizontal road reaches a rise the maximum power of the engine may be utilized by causing the engine to run at full number of revolutions, while the turning moment required to act on the driving wheels automatically adjusts itself to that value corresponding to the rise and the engine power output.

The structure above described having divided blades may, as stated, also be applied to water turbines and rotary pumps (centrifugal pumps), gas turbines, compressors and the like. As far as turbines are concerned the invention enables variation of the

number of revolutions and the turning moment. As regards centrifugal pumps the lifting height and amount of water lifted 45 may be varied.

What I claim is:

1. In a fluid device, blade wheels, a fluid channel in said wheels, blades on said wheels having independently movable portions, concentric members carrying said movable portions, and a common shaft carrying said members, said members being adapted to be locked to said shaft so as to rotate therewith, or be released therefrom so as to rotate independently thereof. 55

2. In a fluid device, blade wheels, a fluid channel in said wheels, blades on said wheels having independently movable portions, concentric members carrying said movable portions, a common shaft carrying said members, and means adapted to lock said members to said shaft or release them therefrom. 60

3. In a fluid device, blade wheels, a fluid channel in said wheels, blades on said wheels having independently movable portions, concentric members carrying said portions, a common shaft carrying said members, a ratchet mechanism to lock said members to said shaft or release them therefrom, and a 65 control mechanism to automatically control the operation of said ratchet mechanism.

4. In a fluid device, blade wheels, a fluid channel in said wheels, blades on said wheels having independently movable portions, concentric members carrying said portions, a common shaft carrying said members, a ratchet mechanism to lock said members to said shaft or release them therefrom, and a 70 centrifugal governor to control the operation of said ratchet mechanism. 75

In testimony whereof I have signed my name.

ANTENOR NYDQVIST.
